UNITED STATES PATENT OFFICE.

JOHN H. GRANT, HENRY C. GOOD SPEED, AND THEODORE M. FOOTE, OF BOSTON, MASSACHUSETTS; SAID GRANT ASSIGNOR, BY DIRECT AND MESNE ASSIGNMENTS, TO SAID GOOD SPEED AND FOOTE, AND FRANKLIN REED, OF BATH, MAINE.

LATCH.

SPECIFICATION forming part of Letters Patent No. 353,025, dated November 23, 1886.

Application filed September 24, 1886. Serial No. 214,405. (No model.)

To all whom it may concern:

Be it known that we, JOHN H. GRANT, HENRY C. GOOD SPEED, and THEODORE M. FOOTE, all of Boston, in the county of Suffolk and State 5 of Massachusetts, citizens of the United States, have invented a new and useful Improvement in Latches, of which the following is a full, clear, and exact description, reference being had to the accompanying drawings, forming a 10 part of this specification, in explaining its nature.

The invention relates especially to a latch adapted for use in fastening or securing doors or other similar devices which require to be held quite tightly in place—such, for instance, as a refrigerator-door; and it comprises a swing- 15 ing arm having a pivot or stud by which it is fastened to a holding-plate provided with a handle and with a latch-bar; also a catch which 20 comprises, preferably, two lugs or projections extending from a common fastening and holding block having tapering or wedge-shaped surfaces and a latch-engaging catch, also having a wedge-shaped or inclined surface, a notch 25 or recess, and a thumb-piece or knob, said catch pivoted to the block or blocks, adapted to be moved by the engagement of the latch therewith and to automatically engage the latch and hold it after it has been brought in 30 contact with the inclined surfaces of the block or blocks and moved thereon to close the door.

Referring to the drawings, Figure 1 is a view in perspective of a part of a door-jamb and door with our latch in place thereon. Fig. 2 35 is a view in perspective showing the latch so arranged that the handle thereof will fall by gravity upon its release. Fig. 3 is a view, partly in horizontal section and partly in elevation, of our said improvement. Fig. 4 is a 40 view principally in vertical section through the catch-member of the device.

A represents one member of the latch, and B the other member. Preferably the member A is secured to a stationary jamb or part, and the member B to the door or movable part to 45 be fastened.

The part A comprises the plate a, having screw-holes a' for the reception of the screws

fastening it in place, the headed standard or post a², and the swinging arm a³, which is pivoted upon said post or stud and secured to the plate thereby, and has a stop, a⁴, adapted to come in contact with the stationary stops a⁵ upon the said plate a, the extension a⁶, which forms the handle, and the section a⁷, which forms the latching part. It is desirable for ordinary purposes that the latch-handle be placed so that it shall extend upward from the stud or post and be brought or moved downward to engage the catch, and when this is the case 50 we prefer to use a spring, a⁸, for automatically turning the latch-handle from a horizontal to a vertical position upon the release of the catch. If, however, the arrangement shown in Fig. 2 is employed—that is, a construction which permits the latch-handle to be moved upward to engage the catch—then the latch-handle will 55 need no spring upon the release of the catch, as it will drop by gravity to the desired position.

The second member, B, of the latch or fastening devices comprises a plate, b, having screw-holes b' for the reception of fastening-screws b², the blocks b³, extending from said plate and having rounded, curved, or inclined surfaces b⁴, the catch b⁵, which has inclined or rounded surfaces b⁶, the notch or recess b⁷, the handle or arm b⁸, and the foot b⁹. It is pivoted to the blocks b³ by the pivot b¹⁰, so that the foot b⁹ shall project upon the outer surface of the plate, and the surface of the latch be substantially parallel with the surfaces of the blocks b³ at the end of the inclined or rounded sections. This will, of course, bring a section of the catch above the surfaces of these blocks. The catch is also pivoted so as to be moved 80 downward or inward against the pressure of a spring, b¹¹, which constantly acts to push or throw the catch part outward and keep the foot in contact with the plate, so that after the swinging arm rides over the surfaces of the blocks b³, depressing or moving inward the catch, upon reaching the notch or recess b⁷ the catch is immediately moved outward, so that the swinging arm is held engaged thereby. 85

The arm or handle b⁸ serves two purposes: 90 first, to push inward the catch to release the

swinging arm, and, second, as a handle by which the door or other part to which the catch is secured may be moved.

When desired, a lock of any suitable construction can be placed in or upon the member B so that its bolt shall operate to lock the catch after it has engaged the swinging arm.

Of course it is not necessary to use two blocks, b³, as one will answer; but the use of two provides an opportunity for a stronger and more durable construction; but we do not limit ourselves to the use of two.

It will be seen that a latch of this general form of construction is very desirable, in that it provides means for moving the door or other moving part to its seat by the employment of the wedge-shaped or inclined surfaces before it latches; also, that the swinging arm is automatically engaged with the catch when the door has been brought or moved into proper position; also, that by moving the catch inward the swinging arm is disengaged; also, that the catch and operating arm or handle also serve as the handle or knob of the door or other part.

It is obvious that this form of construction can be used not only for refrigerator and other doors, but for gates, covers, or in any swinging part which requires to be fastened to a fixed or stationary part.

Having thus fully described our invention, we claim and desire to secure by Letters Patent of the United States—

1. The combination, with one member of a latch, which member comprises a plate having 35 a stud or post, a², a swinging arm, a³, which swinging arm is provided with a handle, a⁶, and a latching part, a⁷, of another member of said latch, which other member comprises a plate, b, provided with one or more blocks, b³, 40 which blocks have inclined or rounded or tapering surfaces b⁴, and catch b⁵, which catch has the notch or recess b⁷, all substantially as described.

2. The combination, in a member of a latch, 45 of a plate, a, a post or stud, a², supporting a swinging arm, a³, comprising a handle, a⁶, a latching part, a⁷, with the stops a⁸, and spring a⁹, substantially as described.

3. The member of a latch, comprising a plate, 50 b, having one or more blocks, b³, provided with rounded, inclined, or tapering surfaces, the catch b⁵, pivoted thereto, and spring b¹¹, substantially as described.

4. The member of a latch, comprising a plate, 55 b, having one or more blocks, b³, provided with rounded, inclined, or tapering surfaces, the catch b⁵, pivoted thereto, having the arm or handle b⁸, substantially as described.

JOHN H. GRANT.
HENRY C. GOODSPEED.
THEODORE M. FOOTE.
